UNITED STATES PATENT OFFICE.

EMIL KANTUREK, OF ZURICH, SWITZERLAND.

COIN-DELIVERING APPARATUS.

1,183,072.

Specification of Letters Patent. Patented May 16, 1916.

Application filed November 6, 1915. Serial No. 60,082.

To all whom it may concern:

Be it known that I, EMIL KANTUREK, a citizen of Switzerland, residing at Zurich, Switzerland, have invented certain new and useful Improvements in Coin-Delivering Apparatus, of which the following is a specification.

The object of the present invention is a coin delivering apparatus, embodying a plate divided into two equal parts turning on hinges.

The annexed drawing represents an example of the object and shows: Figure 1, a side view; Fig. 2, a plan.

Referring to the drawing, *a* is the base plate, which is preferably circular in form. Thereon small pillars *b* are vertically erected which at their top are provided with hinges *c* acting as pivots of two halves of a coin delivering plate *d*, in such a manner that these two half plates when in the position for use are always kept in a horizontal line. This is attained by arranging for the center of gravity to be on the two adjoining sides of each plate half *d'*, (resting on pillar *e*).

When using the paying plate, lay the hand flat on one of the extensions *f*, fixed at the end of each half of the plate, press same down and one half of the plate will assume a sloping position as shown in dotted lines in the Fig. 1, thus allowing the money on the plate to slip down into the hand.

Patent claim.

A coin delivering apparatus, comprising a base plate, a pair of oppositely disposed pillars adjacent the edge of said plate, one half of a coin delivering plate pivoted to each pillar, each of said plate halves having its center of gravity over substantially the middle of the base plate, and a third pillar at approximately the middle of the base plate upon which the inner edges of the said plate halves are adapted to rest.

In testimony whereof I have affixed my signature in presence of two witnesses.

EMIL KANTUREK.

Witnesses:

W. R. WHINDA,
CARL GUMBER.
